(57) **CLAIM**

The ornamental design for an electric drying machine for laundry purpose, as shown and described.

DESCRIPTION

FIG. 1 is a front perspective view of the electric drying machine for laundry purpose showing our new design;

FIG. 2 is a front view thereof;

FIG. 3 is a back view thereof;

FIG. 4 is a left side view thereof;

FIG. 5 is a right side view thereof;

FIG. 6 is a top plan view thereof; and,

FIG. 7 is a bottom plan view thereof.

The broken lines depict portions of the electric drying machine for laundry purpose that form no part of the claimed design.

1 Claim, 7 Drawing Sheets
